(57) **CLAIM**

The ornamental designs for a pipette tip tray assembly, as shown and described.

DESCRIPTION

FIG. 1 is an exploded perspective view of a pipette tip tray assembly including a tray lid, pipette tip rack, and tray base;

FIG. 2 is a closed assembled perspective view of the pipette tip tray assembly;
FIG. 3 is a top view thereof;
FIG. 4 is a right side view thereof;
FIG. 5 is a front view, thereof;
FIG. 6 is a back view thereof;
FIG. 7 is a left view thereof;
FIG. 8 is a bottom view thereof;
FIG. 9 is a perspective view of the pipette tip rack portion installed in the tray base portion with the bottom view being identical to the tray bottom shown in FIG. 8;
FIG. 10 is a top view thereof;
FIG. 11 is a front view thereof;
FIG. 12 is a right side view thereof;
FIG. 13 is a back view thereof;
FIG. 14 is a left side view thereof;
FIG. 15 is a perspective upside down view of the lid portion;
FIG. 16 is a top view thereof;
FIG. 17 is a front view thereof;
FIG. 18 is a left side view thereof;
FIG. 19 is a right side view thereof;
FIG. 20 is a back view thereof;
FIG. 21 is a bottom or inside view thereof;
FIG. 22 is a perspective view of a pipette tip rack portion;
FIG. 23 is a top view thereof;
FIG. 24 is a front side view thereof;
FIG. 25 is a right side view thereof;
FIG. 26 is a back view thereof;
FIG. 27 is a left side view thereof;
FIG. 28 is a bottom view thereof;
FIG. 29 is a perspective bottom view thereof;

FIG. 30 is a perspective view of the tray base portion with the bottom view being identical to the tray bottom shown in FIG. 8;
FIG. 31 is a top view thereof;
FIG. 32 is a front view thereof;
FIG. 33 is a right side view thereof;
FIG. 34 is a back view thereof;
FIG. 35 is a left side view, thereof;
FIG. 36 is an enlarged partial top view of the lid and pipette tip rack clip receptacles shown in FIG. 31 at "36";
FIG. 37 is a perspective cross-sectional view of the pipette tip tray assembly as shown in FIG. 2 taken along line 37-37;
FIG. 38 is an enlarged partial perspective view of the lid clip engaged in the base tray in the closed position shown in FIG. 37 at "38";
FIG. 39 is a top view of the pipette tip tray assembly in the open position;
FIG. 40 is a cross-sectional view of the pipette tip tray assembly as shown in FIG. 39 taken along line 40-40;
FIG. 41 is an enlarged front view of the lid clip engaged in the base tray in the open position shown in FIG. 40 at "41";
FIG. 42 is a top view of the pipette tip tray assembly in the open position;
FIG. 43 is a cross-sectional view of the pipette tip tray assembly as shown in FIG. 42 taken along line 43-43; and,
FIG. 44 is a cross-sectional view of the pipette tip tray assembly as shown in FIG. 42 taken along line 44-44.
Broken lines are included for the purpose of illustrating portions of the pipette tip tray assembly that forms no part of the claimed design.
